J. H. HANKINSON.
ANDIRON.

No. 17,170.

Patented Mar. 8, 1887.

UNITED STATES PATENT OFFICE.

JOHN H. HANKINSON, OF NEW YORK, N. Y.

DESIGN FOR AN ANDIRON.

SPECIFICATION forming part of Design No. 17,170, dated March 8, 1887.

Application filed July 9, 1885. Serial No. 171,124. Term of patent 7 years.

To all whom it may concern:

Be it known that I, JOHN H. HANKINSON, a citizen of the United States, residing at New York, in the county and State of New York, 5 have invented and produced a new and original Design for Andirons, of which the following is a specification, reference being had to the annexed drawing, forming a part thereof.

The figure represents a front elevation of 10 my newly-designed andirons, exhibiting the ornamentation thereon.

The prominent distinguishing features of 15 this design consist of the representation of a satyr-like mask, A, forming the top or apex of the andiron, the central daisy rosette, B, on the front of the standard C, above and below which rosette the undulating ribbon form of ornament is formed, extending down to the rectangular Greek feet D below the rosette.

I claim—

The design for andirons shown and described, consisting of the representation of a satyr-like mask, A, at the top or apex, central daisy rosette, B, on the standard, and the undulating ribbon form or ornament on the 25 standard above and below the rosette and on the legs.

JOHN H. HANKINSON.
